UNITED STATES PATENT OFFICE

2,614,679

CONVEYER AND TRANSFER MECHANISM
FOR WRAPPING MACHINESOscar Sandberg, Toledo, Ohio, assignor to Lynch
Corporation, Anderson, Ind., a corporation of
Indiana

Application May 2, 1949, Serial No. 90,990

10 Claims. (Cl. 198—24)

1

This invention relates to a means for feeding articles to an intake conveyor of a wrapping machine and particularly articles such as cookies or "sandwiches" so that they can be placed in a feeding conveyor, the feeder mechanism being operable to remove a predetermined number or "stack" of the cookies or sandwiches at a time and position them where they can be engaged by a former plate and lowered into the pocket of a pocket conveyor which conveys the stack to a position where it can be engaged by a vertical ram for moving it into the wrapping mechanism of the wrapping machine.

One object of the invention is to provide an inclined feed conveyor and a measuring means to permit the advance of only a predetermined number or stack of articles to a position where they may be engaged by a horizontal ram which moves them away from the feed conveyor to a position for introduction into a pocket conveyor, a reciprocating former plate adapted to then engage the stack of articles at this position and shift the cookies of the stack to an aligned position prior to moving them into a pocket of the pocket conveyor so that they rest in proper position therein for being conveyed to the wrapping mechanism.

Another object is to provide a means for adjusting the measuring device and parts of the feeder mechanism to accommodate a different number of articles with a minimum of operations necessary to convert from one size stack of articles to another.

Still another object is to provide a feed conveyor delivering articles at right angles over a pocket conveyor with a measuring rod reciprocable into the feed conveyor to engage articles therein and permit the articles to be advanced until a predetermined number of them are in position over the pocket conveyor to be engaged by a ram that moves longitudinally of the pocket conveyor and engages the predetermined number of articles to be placed in a pocket of the pocket conveyor, this ram moving the predetermined number or stack of articles to a position out of alignment with the feed conveyor where they may be engaged by a former plate and moved into a pocket of the pocket conveyor thereby.

A further object is to provide the ram that moves longitudinally of the pocket conveyor of such construction that it can reciprocate continuously to engage a stack of articles when the measuring rod is in operation, and to straddle the measuring rod when it is not in operation but holds the articles back from position in front of the ram.

5 Still a further object is to provide a control lever for controlling the reciprocation of the measuring rod so as to stop its operation when desired, the control lever arrangement being designed to permit stopping of the measuring rod only in the position it assumes when extended into the feed conveyor for preventing the articles from being fed thereby to a position in front of the ram.

10 With these and other objects in view, my feeder for wrapping machines consists in the construction, arrangement and combination of the various parts of which it is composed whereby the objects contemplated are attained as hereinafter 15 more fully set forth, pointed out in my claims and illustrated in the accompanying drawings in which:

20 Figure 1 is a left side elevation of part of a wrapping machine such as shown in my copending application above referred to and to which my present feeder has been applied;

25 Figure 2 is a similar left side elevation and is a continuation of the right hand end of Figure 1, this figure showing most of the mechanism of the feeder;

30 Figure 3 is an enlarged rear end view as viewed from the righthand end of Figure 2, some of the operating parts being omitted as they are shown in later figures;

35 Figure 3^a is a sectional view on the line 3^a—3^a of Figure 3 showing an automatic release mechanism;

Figure 3^b is a similar view of a portion of Figure 3^a showing certain parts thereof in a different position;

Figure 4 is an enlarged sectional view on the line 4—4 of Figure 1, the scale however being somewhat smaller than Figure 3;

Figure 5 is an enlarged sectional view on the line 5—5 of Figure 2, the scale being the same as Figure 3;

Figure 6 is a plan view looking forward (toward the left in Figure 2) and showing the feed conveyor, the scale being the same as Figure 2;

Figure 7 is a rear elevation of Figure 6 as taken on the line 5—5 of Figure 2;

Figure 8 is an enlarged sectional view on the line 8—8 of Figure 7;

Figure 9 is a sectional view on the line 9—9 of Figure 8;

Figure 10 is an enlarged plan view looking forward and showing the portion of Figure 2 indicated by the line 10—10; and

55 Figure 11 is a sectional view on the line 11—11

of Figure 10, this view being taken from the right side of the machine.

On the accompanying drawings I have used the reference numerals 16 and 18 to indicate vertical frame members which are connected at the top by a table 20. A pair of rods 22 and 24 are secured in the frame member 18 and extend rearwardly, their rear ends being supported by a vertical frame member 26 as shown in Figure 2.

Cross shafts 28 and 30 (Figure 1) are journaled in bearings supported by the frame member 16 and a cross shaft 32 (Figure 2) is journaled in bearings supported by the rods 22 and 24. Sprockets 34, 36 and 38 are mounted on the shafts 28, 30 and 32, respectively, and a chain 40 extends around the three sprockets and passes over an idler wheel 45 (Figure 2) supported by brackets 47 and 49 and fittings 51 and 53 on the rods 22 and 24. Periodically spaced on the chain 40 are channeled shaped pockets 42 adapted to receive stacks of articles to be wrapped.

Adjacent the sprockets 34 and 36 (Figure 1) a vertical ram 55 is provided for elevating articles from the pocket conveyor into a rotary head 57 journaled on a shaft 59 in a pair of side frames 61 which are mounted on the table 20. This rotor includes pockets (not shown) to receive the articles and wrap them as fully disclosed in my above mentioned copending application. The ram head 55 is mounted on a cross head 63 which is vertically slidable on stationary guide rods 65 and is reciprocated by means of an arm 71 on the rock shaft 114 operatively connected by links 73 with the cross head.

The pocket conveyor 40-42 is driven by a Geneva movement including a notched disk 43 on a shaft 44 and an arm 46 having a roller 48 to coat therewith, the arm being mounted on a continuously rotating shaft 50 which rotates once each cycle of the wrapping machine as disclosed more fully in my copending application. A sprocket 52 mounted on the shaft 44 drives a sprocket 54 on the pocket conveyor by means of a chain 56 extending around the two sprockets and around an idler sprocket 58. The pocket conveyor 40-42 is thus driven intermittently.

Referring to Figures 2, 6 and 7, a conveyor belt 60 is provided trained around a drive pulley 62 and an idler pulley 64. The belt slides on a supporting plate 66 connected at its left end to a supporting rod 68 extending between brackets 70 and 72 which, as shown in Figure 7, are mounted by means of hubs 74 surrounding the supporting rods 22 and 24.

The outer end of the plate 66 is supported by a yoke 76 connected with a strut 78 which in turn is connected with a bracket 80 secured to a base plate 82 of the machine. The feed conveyor further includes a pair of side plates 84 supported by rods 86 in hubs 88 of brackets 90. Set screws 92 are used to retain the rods in various adjusted positions so that the side plates 84 can be adjusted to accommodate cookies or sandwiches 94 of slight difference in diameter as best shown in Figure 8. The side plates 84 can also be adjusted longitudinally of the plate 66 by means of clamp screws 96 through slots 98 of the brackets 90 as shown in Figure 9, the clamp screws being threaded into the plate 66.

For propelling the conveyor belt 60, I provide a ratchet wheel 100 operatively connected with the drive pulley 62 and actuated by a pawl 102. The pawl is engaged with the teeth of the ratchet wheel by a spring 104 and is carried by an oscil-

latable arm 106 which in turn is connected by a link 108 with an arm 110 on a driven rock shaft 112.

Referring to Figure 2 the driven rock shaft 112 is actuated by a drive rock shaft 114. The rock shaft 114 in turn is actuated as disclosed in Figure 4 by an arm 115 depending therefrom and connected by a link 117 with a crank 119 on a main drive shaft 123. The shaft 123 is suitably connected by bevel gears and a chain connection 123a as disclosed in my Patent 2,283,097 with the shaft 50 whereby the shaft 50 rotates at the same speed as the shaft 123 which is once per cycle of operation of the wrapping machine.

The driven rock shaft 112 is then oscillated from the drive rock shaft 114 through a clutch mechanism including a disk 116 on the shaft 114 and a companion disk 118 on the shaft 112. A pin 120 is slidably mounted in the disk 118 and is adapted to enter a socket 124 in the disk 116, the pin being spring biased to a position out of the socket by a spring 148 at the rear of the feeder to be described later.

Means is provided to force the pin into the socket 124 at the will of the operator comprising a bracket 128 attached to the rock shaft 112 and having a projection 130. The pin 120 is also slidable through the projection 130 and is threaded in a fitting 132 which is connected by a pivot pin 134 to a link 136. A collar 138 is provided on the pivot pin 134 to permit pivoting action, but prevent the pin 120 from dropping out of the fitting 132.

The link 136 is connected by a pivot pin 140 to a clutch lever 142. The clutch lever is pivoted at 144 to a bracket 146 and extends upwardly at an angle as shown in Figure 3 to terminate at a position at the right side of the machine where it is convenient to be engaged by an operator standing in position to place articles in the feed conveyor. The spring 148 is connected with the lever 142 and with the frame member 26 for the purpose of biasing the lever toward the frame member, thus tending to withdraw the pin 120 from the socket 124 of the disk 116.

A latch bar 150 best shown in Figure 3a is pivoted at 152 to the frame member 26 and is biased upwardly toward the clutch lever 142 by a spring 154. The latch bar has a notch 156 normally receiving the clutch lever and a finger 158 of an arm 160 is adapted to engage and depress the latch bar 150 each cycle of operation. The arm 160 is mounted on the driven rock shaft 112 by means of a second arm 162 (see Figure 3), a stud 164 carried thereby and a clamp screw 166 adapted to clamp the arm 160 at a desired adjusted position on the stud 164.

The arm 162 is also provided with a clamp screw 163 so that both the angular relation of the finger 158 to the rock shaft and its distance therefrom may be adjusted by loosening the screws 163 and 166 and retightening them after the adjustment is made. Additionally, the finger 158 is carried by a plate 159 having a slot 161 through which a clamp bolt 165 extends so that the finger can be adjusted up or down on the bracket 160.

The rock shaft 112 is normally held in the position shown in Figure 3 by a spring 168 connected at one end therewith and at its other end to a strap 170 secured at 172 to the frame member 26.

A manually releasable latch lever 174 is provided for the clutch lever 142, this lever being pivoted to the frame member 26 at 176 as shown

in Figure 2. The latch lever 174 has a notch 178 to receive the clutch lever as illustrated in this figure.

The cookies or sandwiches which are placed on the conveyor belt 66 are moved toward the ratchet wheel 109 (to the left in Figure 7) by the belt to a position against a plate 180. This plate as shown in Figure 10 is adjustably supported by means of rods 182 and 184 which are slidable in bosses of a bracket 186 and the bracket 70 respectively. The bracket 186 is supported on the rod 68. Set screws 188 are provided to retain the rods 182 and 184 in their adjusted positions.

The belt 66 is operated at a speed slightly greater than that necessary to bring the desired number of cookies or sandwiches into position against the plate 180 for being engaged by a horizontal ram shown in Figures 10 and 11. The ram just referred to is in the form of a plate 190 slid- 20 able in guides 192 and a second plate 194 secured thereto with a spacer 196 between them as shown in Figure 11 in order to provide a ram that properly contacts with the cookies or sandwiches 94 as shown without interfering with a measuring rod 256 between the plates and which will be described in detail later in the specification. The retracted position of the ram is illustrated by dot and dash lines in this figure.

The horizontal ram 190-194 is operated by a lever 198 (see Figure 10) connected with the ram by a link 298 and pivotally mounted at 292 on an extension 204 of the bracket 72 as shown in Figure 2. The other end of the lever 198 has a link 206 connected therewith which extends forwardly and is pivoted at 208 to a crank arm 210 as shown in Figure 1. The crank arm 210 is secured to a shaft 212 journaled on the table 20 and provided with a sprocket 214 which is operatively connected by a chain 216 with a sprocket 218 on the shaft 50. This chain extends around idlers 220 and 222. The horizontal ram 190-194 is thereby reciprocated once each cycle of the wrapping machine.

The ram 190-194 pushes the stack of cookies or sandwiches containing the desired number from alignment with the belt conveyor 66 to a position just ahead of the belt, such position being shown at 94^a in Figure 10. A former plate 224 (see Figure 5 also) is adapted at this position to engage the stack of sandwiches and force them down into a pocket 42 of the pocket conveyor.

The cookies are held at this position before the former plate engages them by means of the plate 180 and a plate 226 (see Figure 10) having its rear end pivoted by means of hook lugs 228 to a stationary plate 230. The forward end of the pivoted plate 226 carries a rod 232 which is slid- 45 able in the stationary plate 230, and has a collar 234 to engage the plate 230. A second collar 236 is secured to the rod and connected by a spring 238 with the plate 230, thus biasing the plate 226 toward the stack of cookies and holding them securely between the plates 180 and 226. The former plate 224 is then adapted to engage the stack of cookies which are at a slight angle because of the inclination of the feed conveyor 66 and straighten them so that they are all level as they enter the pocket of the pocket conveyor.

The former plate 224 is carried by a rod 240 slidable in a guide 242 supported by an extension 244 of the bracket 70 as shown in Figure 5. The upper end of the rod 240 is connected by means of a pivot pin 246 to a link 248, the connection being of the ball and socket type. The lower end of the link 248 is connected by a combined pivot 70

and clamp bolt 250 to an arm 252 extending from the rock shaft 112. This arm is slotted as indicated at 254 so that the stroke of the former plate 224 may be adjusted.

A measuring or stroke regulator rod 256 is provided as shown in Figure 5 having its left end pivoted to an arm 258 on the rock shaft 112 and its other end slidable in a guide tube 260. This tube is welded or otherwise suitably secured to the plate 180.

Practical operation

In the operation of my feeder for wrapping machines an attendant places the cookies or sandwiches on the conveyor belt 66 and they are propelled toward the left in Figure 5 to a position against the measuring rod 256, it being in the dotted position the major portion of a cycle of operation.

Periodically the rod 256 is retracted to the position shown by solid lines during which time the conveyor belt is propelled by the ratchet mechanism 100-104 and therefore advances the row of sandwiches causing them to follow the measuring rod 256. After this rod reaches the full line position the horizontal ram 190-194 moves forwardly from the dot and dash line position illustrated in Figure 11 to the full line position shown therein, this position also being shown in Figure 10. This advances the stack of sandwiches to a position under the former plate 224 at which position they are held suspended above a pocket of the pocket conveyor by the spring pressed plate 226.

The feeder is shown adjusted for four sandwiches (one sandwich being two cookies or crackers with a filling between them) but by adjusting the pivot 257 upwardly in the slot 259 of the arm 258 it can be adjusted for five sandwiches since its travel will be longer in a direction toward the left in Figure 5, that is the solid line position will be one sandwich farther to the left.

Adjustment of the feeder for five sandwiches also requires that the plate 180 be adjusted toward the left and this is accomplished by loosening the set screws 188 to permit the rods 182 and 184 to be slid toward the left to accommodate the additional sandwiches. The pocket conveyor and the wrapping mechanism are also similarly adjusted but this forms no part of my present invention.

At this time in the cycle of operation the former plate 224 is lowered for leveling up the stack of sandwiches and moving them from position 94^a in Figures 10 and 11 downwardly to the dot and dash line position 94^b in Figure 11. This of course is during the time the pocket conveyor is stationary. The stack of sandwiches then travels forwardly between side plates 67 of the pocket conveyor and eventually reaches the position in alignment with the ram head 55 in Figure 1. The ram is then elevated through a hole 69 in the bottom of the pocket for elevating the stack of sandwiches into the rotary wrapping head 57.

The wrapping machine is so constructed that most of its parts operate continuously but a wrapper is not fed to wrapping position unless there is a stack of sandwiches to be wrapped in such wrapper. The horizontal ram 190-194 also operates each cycle of operation of the machine.

It is desirable to stop the operation of the feeding mechanism however in the event that sandwiches become damaged when placing them in

the feed conveyor or whenever broken sandwiches are to be removed therefrom. For this purpose, the clutch lever 142 is provided and is retained in the operative position of Figure 2 against the bias of the spring 148 by the manual latch lever 174 and particularly the left side of the notch 178. To stop the feeder it is merely necessary to lift the latch lever 174 whereupon the spring 148 pulls the lever 142 toward the frame member 26 thereby tending to retract the link 136 10 and accordingly retract the pin 120 from the socket 124. The latch bar 150 however holds the lever 142 against such movement as evident from an inspection of Figure 3^a except when the finger 158 depresses the latch bar as in Figure 3^b when 15 the rock shaft 112 reaches its clockwise limit of movement (counter-clockwise limit shown in Figures 3 and 3^a). Thus if the measuring rod 256 is not at its farthest in limit of movement relative to the feed conveyor 60 when the latch lever 174 is lifted, the latch bar 150 will hold the lever 142 against movement (dotted position of Figure 3^b) to retract the pin 120 and such retraction will occur only when the finger 158 depresses the latch bar 150 to the full line position in this figure. This operation prevents the pin 120 being withdrawn from the socket 124 except when the spring 168 is stretched least and eliminates the possibility of the spring slamming the parts to the clockwise limit of oscillation of the rock shaft 112. 20

Also in order to stop the measuring rod in the dotted line position of Figure 5, it is desirable that the clutch pin 120 is not retracted until the clockwise limit of oscillation of the rock shaft 112 is reached at which position it is held by the spring 168. This is accomplished by the proper relation of the finger 158 with respect to the latch bar 150 so as to engage the latch bar and lower it at the clockwise limit of oscillation. 30

Subsequently when it is desirable to cause operation of the rock shaft 112 again the lever 142 is swung rearwardly to the full line position of Figure 2 and latched by gravity acting on the latch lever 174. This forces the pin 120 into the 45 socket 124 when the socket reaches a position of alignment with the pin for connecting the driven rock shaft 112 with the drive rock shaft 114. The feeding mechanism is thus under instant control of the attendant but the declutch action is automatically withheld until the proper time in the cycle of operation of the machine.

Some changes may be made in the construction and arrangement of the parts of my device without departing from the real spirit and purpose of my invention, and it is my intention to cover by my claims any modified forms of structure or use of mechanical equivalents which may be reasonably included within their scope.

I claim:

1. In a feeder for wrapping machines, a feed conveyor, a ratchet drive therefor, a measuring rod, a guide tube therefor, means for reciprocating said measuring rod in said guide tube for contacting a row of articles in said feed conveyor, means for operating said ratchet drive for causing the articles in the feed conveyor to follow said measuring rod when it moves in a feeding direction, a ram adapted to engage a predetermined number of the articles and move them out of alignment with said feed conveyor after said measuring rod has reached its outer limit of movement, spring biased plates between which said plurality of articles are moved by said ram, a reciprocable former plate adapted to engage

5 said plurality of articles and move them from their position between said plates into a pocket of a pocket conveyor, and means for operating said measuring rod comprising a drive rock shaft, a driven rock shaft, a pin type clutch for connecting said driven rock shaft to said drive rock shaft, a clutch lever for engaging said pin, a spring for disengaging it, said clutch lever controlling the engagement and disengagement, a latch lever for said clutch lever in the engaged position, a latch bar for said clutch lever in the engaged position, said latch lever being manually releasable, and said latch bar being normally engaged but periodically disengaged each cycle of operation of the wrapping machine for permitting said spring to effect disengagement only when said measuring rod is at its inner limit of movement, and a second spring for normally biasing said measuring rod to said limit of movement.

2. In a feeder for wrapping machines, a feed conveyor, a measuring rod, a guide tube therefor, means for reciprocating said measuring rod in said tube for contacting a row of articles in said feed conveyor, a ram adapted to engage a predetermined number of the articles and move them out of alignment with said feed conveyor, spring biased plates between which said plurality of articles are moved by said ram, a reciprocable former plate adapted to engage said plurality of articles and move them from their position between said plates into a pocket of a pocket conveyor, and means for operating said measuring rod and said feed conveyor comprising a drive rock shaft, a driven rock shaft, a pin type clutch for connecting said driven rock shaft to said drive rock shaft, a clutch lever for engaging said pin, a spring for disengaging it, said clutch lever controlling the engagement and disengagement, a latch lever 40 for said clutch lever in the engaged position, a latch bar for said clutch lever in the engaged position, said latch lever being manually releasable, and said latch bar being normally engaged but periodically disengaged each cycle of operation of the wrapping machine for permitting said spring to effect disengagement only at a predetermined position of the parts.

3. In a feeder for wrapping machines, a feed conveyor, a measuring rod, a guide tube therefor, means for reciprocating said measuring rod in said tube for contacting a row of articles in said feed conveyor, a ram adapted to engage a predetermined number of the articles and move them out of alignment with said feed conveyor, spring biased plates between which said plurality of articles are moved by said ram, a reciprocable former plate adapted to engage said plurality of articles and move them from their position between said plates into a pocket of a pocket conveyor, means for operating said measuring rod and said feed conveyor comprising a drive rock shaft, a driven rock shaft, a pin type clutch for connecting said driven rock shaft to said drive rock shaft, a clutch lever for engaging said pin, and a spring for disengaging it.

4. In a feeder for wrapping machines, a feed conveyor, a measuring rod, a guide tube therefor, means for reciprocating said measuring rod in said tube for contacting a row of articles in said feed conveyor, a ram adapted to engage a predetermined number of the articles and move them out of alignment with said feed conveyor, means for operating said measuring rod and said feed conveyor comprising a drive rock shaft, a driven rock shaft, a pin type clutch for connecting said

driven rock shaft to said drive rock shaft, a clutch lever for engaging said pin, a spring for disengaging it, said clutch lever controlling the engagement and disengagement, a latch lever for said clutch lever in the engaged position, a latch bar for said clutch lever in the engaged position, said latch lever being manually releasable, and said latch bar being normally engaged but periodically disengaged each cycle of operation of the wrapping machine for permitting said spring to effect disengagement only at a predetermined position of the parts.

5. In a feeder for wrapping machines, a feed conveyor, a measuring rod, means for reciprocating said measuring rod throughout a limited portion of the discharge end of said feed conveyor for contacting the discharge end of a row of articles in said feed conveyor, said limited portion substantially corresponding to the height of a stack of said articles to be wrapped, means for operating said measuring rod and said feed conveyor simultaneously in a feeding direction, a ram to engage a predetermined number of the articles and move them out of alignment with said feed conveyor after said measuring rod has reached its outer limit of movement, means to receive said plurality of articles moved by said ram, a reciprocable former plate adapted to engage said plurality of articles and move them from their position received in said last means into a pocket of a pocket conveyor, said means for operating said measuring rod and said feed conveyor comprising a drive rock shaft, a driven rock shaft, a pin type clutch for connecting said driven rock shaft to said drive rock shaft, a clutch lever for engaging said pin, and a spring for disengaging it, said clutch lever controlling the engagement and disengagement.

6. A feeder for a wrapping machine having a pocket conveyor comprising a feed conveyor for delivering articles thereto, a measuring rod reciprocable in said feed conveyor, said feed conveyor traveling at right angles to the pocket conveyor, means for stacking the articles and placing a stock in each pocket of the pocket conveyor comprising a ram for engaging a stack of the articles and moving them in a direction at right angles to the feed conveyor, squeeze plates between which the stack is held when moved by said ram, a movable former for engaging the stack and moving it from between said squeeze plates into a pocket of the pocket conveyor, means for cyclically operating said feed conveyor, ram and former, means for operating said measuring rod and said feed conveyor comprising a drive rock shaft, a driven rock shaft, a pin type clutch for connecting said driven rock shaft to said drive rock shaft, a clutch lever for engaging said pin, and a spring for disengaging it, said clutch lever controlling the engagement and disengagement, a latch lever for said clutch lever in the engaged position, a latch bar for said clutch lever in the engaged position, said latch lever being manually releasable, and said latch bar being normally engaged but periodically disengaged each cycle of operation of the wrapping machine for permitting said spring to effect disengagement only at a predetermined position of the parts.

7. A feeder for a wrapping machine having a pocket conveyor comprising a feed conveyor for delivering articles thereto, said feed conveyor traveling at right angles to the pocket conveyor, means for stacking the articles and placing a stack in each pocket of the pocket conveyor com-

prising a horizontal ram for engaging a stack of the articles and moving from alignment with said feed conveyor, squeeze plates for holding the stack when moved by said ram, a vertically movable former for engaging the stack and moving it from between said squeeze plates into a pocket of the pocket conveyor, and means for cyclically operating said feed conveyor, ram and former comprising a drive rock shaft, a driven rock

10 shaft, a pin type clutch for connecting said driven rock to said drive rock shaft, a clutch lever for engaging said pin, a spring for disengaging it, a latch lever for said clutch lever in the engaged position, a latch bar for the clutch lever in the engaged position, said latch lever being manually releasable, and said latch bar being normally engaged but periodically disengaged each cycle of operation of the wrapping machine for permitting said spring to effect disengagement only at a predetermined position of the parts.

15 8. A feeder for a wrapping machine having a pocket conveyor comprising a feed conveyor for delivering articles thereto, said feed conveyor traveling at right angles to the pocket conveyor, means for stacking the articles and placing a stack in each pocket of the pocket conveyor comprising a ram for engaging a stack of the articles and moving them in a direction at right angles to the feed conveyor, squeeze plates between which the stack is moved by said ram, a vertically movable former for engaging the stack and moving it from between said squeeze plates into a pocket of the pocket conveyor, and means for cyclically operating said feed conveyor, ram and former, said last means comprising a drive rock shaft, a driven rock shaft, a pin type clutch for connecting said driven rock to said drive rock shaft, a clutch lever for engaging said pin, a spring for disengaging it, means to insure disengagement only at a predetermined position of the parts, and a second spring for normally biasing said parts to said predetermined position.

20 9. In a feeder of the character disclosed, a feed conveyor for articles to be fed in stacks to a wrapping machine, a measuring rod reciprocable into and out of said feed conveyor, ratchet drive means for said feed conveyor interconnected with said measuring rod to operate the feed conveyor as the measuring rod is retracted from said conveyor, a ram adapted to engage a stack of articles and move them at right angles from said feed conveyor and from position in alignment with said measuring rod to a secondary position, a pair of squeeze plates which hold the stack at the position assumed by reason of the operation of said ram, said ram being bifurcated to straddle said measuring rod and thereby permit operation of the ram when the rod is in its inner limit of movement, means for operating said measuring rod each cycle of operation of the wrapping machine, means for operating said ram only when it is desirable to feed articles to the wrapping machine, said last means including a drive rock shaft and a driven rock shaft, a clutch connection between the two and control means for said clutch connection disengageable only at a predetermined position of the parts when said measuring rod is at its inner limit of movement, and a spring for holding said rod at said limit except when said clutch connection is engaged.

25 10. In a feeder of the character disclosed, a feed conveyor for articles to be fed in stacks to a wrapping machine, a measuring rod reciprocable into and out of said feed conveyor, drive means

for said feed conveyor interconnected with said measuring rod to operate the feed conveyor only as the measuring rod is retracted from said conveyor, a ram adapted to engage a stack of articles and move them from position in alignment with said measuring rod to a secondary position, means to hold the stack at the position assumed by reason of the operation of said ram, said ram being bifurcated to straddle said measuring rod and thereby permit operation of the ram when the rod is in its inner limit of movement, means for reciprocating said measuring rod into and out of said feed conveyor each cycle of operation of the wrapping machine, and means for operating said ram only when it is desirable to feed articles to the wrapping machine, said last means includ-

ing a drive rock shaft and a driven rock shaft, a clutch connection between the two, and control means for said clutch connection to permit disengagement thereof only when said measuring rod is at its inner limit of movement.
